UNITED STATES PATENT OFFICE.

THOMAS B. CASEY, OF BOSTON, MASSACHUSETTS.

INTERNAL-COMBUSTION ENGINE.

1,346,001.

Specification of Letters Patent. Patented July 6, 1920.

Application filed October 25, 1919. Serial No. 333,143.

To all whom it may concern:

Be it known that I, THOMAS B. CASEY, a citizen of the United States, and a resident of Boston, county of Suffolk, State of Massachusetts, have invented a new and useful Internal-Combustion Engine, of which the following is a full, clear, and exact description.

The present invention relates in general to 10 internal combustion engines and has reference more particularly to means for introducing a scavenging medium in the combustion chamber to effect a complete exhaust of all spent gases incident to the firing of the 15 explosive charge.

The primary object of the invention is to provide means for facilitating the exhaust of all spent gases from the combustion chamber of the engine, and thus render the 20 combustion chamber better adapted to receive and fire the explosive charge, whereupon the engine will be capable of operating with a higher degree of efficiency than it has heretofore been possible.

25 Further objects will appear upon reference to the accompanying drawings in which,

Figures 1 to 12 inclusive are vertical sections of a combustion engine constructed 30 in accordance with this invention and showing a complete cycle of operation, and

Fig. 13 is a sectional view of the manifold for introducing the explosive charge and the scavenging medium.

35 Referring now to the drawings by letters of reference the engine proposed by the present invention comprises the cylinder 1, having the usual water cooling jacket 2, surrounding the combustion chamber 3. 4 represents the crank case within which the crank shaft 5 is journaled with the piston rod 6, mounted thereon, and connected to the piston 7, by the wrist pin 8. The cylinder of the engine is peculiarly constructed with 40 a by-pass 9 formed in the side thereof, which provides a communication between the combustion chamber 3, and the crank case 4. The orifices 10 and 11 of this by-pass are 45 opened and closed by the piston 7. The piston is constructed with an orifice 12 which is of a diameter of substantially that of the orifice 10 and may be registered therewith when the piston is in a position to open the communication. The partition 13 between 50 the orifices 10 and 11 is so arranged as to

over-lap and close the orifice 12 in the piston when the piston is in a position to close the communication between the combustion chamber 3 and the crank case 4. A suitable exhaust port 14 is provided in the cylinder 60 through which the spent gases in the combustion chamber 3 may be expelled. This exhaust port is preferably arranged diametrically opposite the orifice 11. Therefore a baffle 15 is presented on top of the piston to 65 deflect the incoming charge through the orifice 11 upwardly of the combustion chamber 3, and preventing the same from being directly discharged through the exhaust port 14. 70

As heretofore stated, the principle involved is to introduce a scavenging medium in the combustion chamber 3 for expelling all spent gases. The preferred embodiment of the invention proposes to introduce this 75 scavenging medium first into the crank case 4, thence through the by-pass 9 and into the combustion chamber 3, where it may perform its intended purpose. Furthermore it is also proposed to introduce the explosive 80 charge into the crank case 4 thus providing an internal combustion engine of the crank compression type. It so happens that the scavenging medium in performing its intended use is practically treated by the engine in the same manner as is the explosive 85 charge, therefore in operation the explosive charge and the scavenging medium will be alternately introduced into the crank case and through the by-pass into the combustion 90 chamber. Both of these elements are slightly compressed in the crank case 4 and acted upon by the piston when introduced into the combustion chamber 3 in practically the same manner, in that they are both compressed by the piston, but of course the scavenging medium is not ignited and therefore does not act in the capacity of that of the explosive charge so far as concerns the 95 driving of the piston. 100

It is intended to introduce the explosive charge and the scavenging medium through a common intake port 16 which is provided in the lower part of the cylinder above the crank case 4 and so positioned that the piston may overlap the same and control the effective area thereof. Connected to the intake port 16 is a manifold which comprises a valved intake 17 for the explosive charge and a valved inlet 18 for the scavenging me- 110

dium. The valves of the intake 17 and the inlet 18 are diametrically opposed and are adapted to be controlled by valves 19 and 20 respectively which are mounted co-axially on a common valve rod 21 which extends vertically of the engine cylinder, one end of which engages a cam 22 mounted on a cam shaft 23. The valves are so arranged that a coil spring 24 interposed between the valve 19 and the top wall of the intake 17 will normally maintain the valve 19 seated, thus closing the intake 17, whereas the position of the valve 20 on the rod 21 will be open. In other words when the valve 19 is closed the valve 20 is opened. Both the valves 19 and 20 may have a threaded engagement with the valve rod 21 so that their relative vertical positions may be adjusted as occasion demands. As stated the explosive 20 charge and the scavenging medium have a common manifold communication with the port 16. Positioned in this communication is a flap valve 25 which is pivoted and adapted to close under its own weight when 25 the port 16 is closed. The scavenging medium is preferably fresh air taken into the manifold from around the engine. The invention is operable in connection with an internal combustion engine which need not 30 be of the crank case compression type although this is preferable.

The cycles of operation are substantially as follows:—

Figure 1 shows the piston at the end of its power stroke, the exhaust port 14 has been uncovered by the piston, and the spent gases are being exhausted from the combustion chamber. A communication between crank case 4 and the combustion chamber 3 has also been established through the by-pass 9 and the scavenging medium which has been slightly compressed in the crank case will be introduced through the by-pass into the combustion chamber where it may act in the 45 capacity to effect a complete exhaust of all spent gases.

In Fig. 2 the piston is started on its compression stroke, and the combustion chamber at this time being filled with the scavenging medium as the piston opens the intake port, the valve 25 will be open and the timing of the valves 19 and 20 is such as to close the scavenging medium inlet and open the explosive charge intake whereupon a communication will be established between the explosive charge intake and the crank case 4, the explosive charge being thus introduced into the crank case, with the piston started on an upstroke compressing the scavenging medium in the combustion chamber.

Fig. 3 shows a continuation of the upstroke of the piston.

Fig. 4 shows the piston at its highest compression point, and at this point the cam 22 will have operated to relieve this lifting

action on the valve rod 21 thus permitting the spring 24 to close the valve 19 and open the valve 20.

As shown in Fig. 5 the piston is now on the down stroke which will compress the explosive charge in the crank case and impart a closing effect to the valve 25.

Fig. 6 shows the piston almost at its lowest point with the orifices 11 and 12 open and the explosive charge compressed in the 75 crank case being introduced into the combustion chamber 3 and the scavenging medium discharging.

Fig. 7 shows the communication through the by-pass completely established and the 80 piston just about to start on its up-stroke.

Fig. 8 shows the piston at its up-stroke, the by-pass closed, and the suction produced in the crank case is introducing another charge of the scavenging medium into the 85 crank case through the intake port.

Fig. 9 shows the piston compressing the explosive charge in the combustion chamber just prior to firing.

Fig. 10 shows the piston at dead center, 90 and

Fig. 11 shows its position practically right after the charge has been fired and on a down-stroke, and

Fig. 12 shows the piston again establishing 95 the communication through the by-pass and permitting the scavenging medium to be introduced through the by-pass into the combustion chamber to effect a complete exhaust of the spent gases.

Having thus described my invention, what I claim as new and desire to secure by Letters Patent is as follows:—

1. In an internal combustion engine, a cylinder having an intake and exhaust port, a crank case, a crank shaft in the crank case, a by-pass having openings for establishing communication between the combustion chamber of the cylinder and the crank case, a piston in the cylinder and provided with an opening adapted to register with one of the openings of the by-pass, the opening of the piston being adapted to be closed by the portion between the openings of the by-pass, a piston rod connecting the piston with the crank shaft, and a manifold connected with the intake port of the cylinder and having a valved inlet for explosive mixture and a valve inlet for a scavenging medium.

2. In an internal combustion engine, a cylinder having an intake and exhaust, a crank case, a crank shaft in the crank case, means for establishing communication between the combustion chamber of the cylinder and the crank case, a piston in the cylinder, a piston rod connecting the piston with the crank shaft, and a manifold connected with the intake of the cylinder and having a valved inlet for the explosive mixture, and a valved inlet for the scavenging medium,

the explosive mixture and the scavenging medium having a common communication with the intake of the cylinder and in which is arranged a flap valve.

- 5 3. In an internal combustion engine, the combination with a cylinder having an intake and exhaust port, a crank case, a piston in the cylinder and means for establishing communication between the combustion chamber of the cylinder and the crank case, of a manifold having an inlet for the ex-
- 10

plosive mixture, an inlet for the scavenging medium communicating with the intake of the cylinder, a flap valve in said communication, the said inlets having valve seats in 15 their bottoms, a sliding rod mounted in the manifold, valves on the rod and adapted to be alternately seated on the valve seats of the said inlets, and means for operating the rod.

THOMAS B. CASEY.
